UNITED STATES PATENT OFFICE.

CHARLES A. STARK, OF UNION CITY, PENNSYLVANIA.

CHAIR-SEAT-SURFACING MACHINE.

SPECIFICATION forming part of Letters Patent No. 682,820, dated September 17, 1901.

Application filed May 23, 1901. Serial No. 61,533. (No model.)

To all whom it may concern:

Be it known that I, CHARLES A. STARK, a citizen of the United States, residing at Union City, in the county of Erie and State of Pennsylvania, have invented certain new and useful Improvements in Chair-Seat-Surfacing Machines; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in chair-seat-surfacing machines, and has for its object the construction of mechanism whereby the surface of a chair-seat can be hollowed out and surfaced at one operation.

20 To accomplish this result, I construct a machine having two rotary cutter-cylinders of suitable contours mounted in a yoke or frame operating upon tracks secured to a sliding carriage to which the chair-seat to be surfaced is secured, these tracks being provided with depressions, so that the cutter-cylinders are raised and lowered during the traverse of the chair-seat thereunder, so as to produce the shaped surface therein desired. These

25 and other features of my invention are hereinafter fully set forth and described, and illustrated in the accompanying drawings, in which—

Figure 1 is a side view in elevation of a chair-seat-surfacing machine embodying my invention. Fig. 2 is a top or plan view of the same. Fig. 3 is a front end view in elevation of the same. Fig. 4 is a top or plan view of the sliding carriage of my machine and the tracks 35 and chair-seat-clamping mechanism thereon. Fig. 5 shows a section of the tracks on the two sides of the sliding carriage, showing the relative arrangement and shapes of the depressions therein.

40 In the drawings illustrating my invention, A is the frame of the machine, B the main driving-shaft mounted therein, and B' b' b' pulleys thereon. In the frame A, preferably near the ends thereof, I mount transverse shafts C D, provided with pulleys c' c' and d' d'. Belts E E' connect the pulleys b' b' on

the shaft B with the pulleys c' d' on the shafts C D, by means whereof they are driven by the shaft B. These features may be varied as desired.

On the shafts C and D, at each side of the frame A, I mount arms F F and G G. These arms F and G extend toward the center of and above the top of the frame A and near the inner ends are provided with transverse braces F' and G', and in bearings f and g in the ends thereof I mount the shafts H and I of rotary cutter-cylinders H' and I', and on the ends of the shafts H and I, I secure pulleys H' and I', from which belts J and J' extend to the pulleys c' and d' on the shafts C and D. The cutter-cylinder H is provided with double curved blades h, and the cutter-cylinder I is provided with curved blades i, as illustrated in Figs. 1 and 2. The shapes 60 of the blades h and i of these cutter-cylinders can, however, be varied according to the shape or shapes of chair-seat surfaces desired. From the ends of the arms F and G, below the bearings f and g therein, arms K 65 and L extend downward and are provided with rollers k and l in the lower ends thereof, as and for the purpose hereinafter set forth. In the top of the frame A, I make longitudinal ways a a, and on these ways I mount a 70 longitudinally-moving carriage M, (see Fig. 3,) preferably provided with a rack m on its under side, with which a pinion m' on a transverse shaft M' intermeshes, this shaft M' being provided with a crank m² for operating 75 it, by means of which mechanism the sliding carriage can be moved back and forth as desired.

On the top of the sliding carriage M, I provide a convenient clamping mechanism N N' 90 n n' for clamping a chair-seat upon the sliding carriage M. On each side of the carriage M, I secure two tracks O and P. On the inside tracks O O the rollers k k on the arms K K travel, and on the outside tracks P P 95 the rollers l l on the arms L L travel, and in each of the tracks P P, I make a curved depression p, and in each of the tracks O O, I make a curved depression o, the shapes of which curves and their relation to each other 100 being clearly shown in Figs. 1, 2, 4, and 5. These curves and their relation to each other

may, however, be varied according to the shape of the depression desired to be made in the chair-seat being surfaced.

In operation a chair-seat is clamped upon the carriage M, and as it is first moved under the cutter-cylinders II' and I' the rollers k travel down into the depressions o in the tracks O, which operates to bring the cylinder II' into contact with the chair-seat, so as to surface the front portion thereof, and the further travel of the carriage causes the rollers l to travel down into the depressions p in the tracks P, which operates to bring the cylinder I' into contact with the chair-seat being surfaced, so as to surface the rear portion thereof.

I have thus described and shown a convenient mechanism for utilizing my invention; but I do not desire to limit myself to the exact construction and arrangement of the parts, as many modifications can be made therein without departing from the spirit of my invention.

Therefore what I claim as new, and desire to secure by Letters Patent of the United States, is—

1. The combination in a chair-seat-surfacing machine, of a frame, a sliding carriage operating in ways upon said frame, two tracks on each side of said carriage having different-shaped depressions therein, two cutter-cylinders mounted in bearings the bearings of one cylinder resting on one track on each side of the carriage, and the bearings of the other cylinder resting upon the others of the tracks

on each side of the carriage, substantially as and for the purpose set forth.

2. The combination in a chair-seat-surfacing machine of a frame, two cutter-cylinders of different shapes mounted on said frame so as to be vertically movable, a sliding carriage on said frame, two tracks on each side of said carriage having different-shaped depressions in the tops thereof, supports on the cylinder-bearings of each cylinder adapted to be engaged by one pair of said tracks as they travel under said supports, substantially as and for the purpose set forth.

3. The combination in a chair-seat-surfacing machine, of a frame, a pair of arms pivoted at each end of said frame, a cutter-cylinder of one shape mounted in the inner ends of one pair of said arms, and a cutter-cylinder of another shape mounted on the inner ends of the other pair of said arms, a carriage operating under said cylinders upon ways on said frame, two tracks of different shape on each side of said carriage, supports under the bearings of one cylinder resting upon the outside tracks on each side of said carriage, and supports under the other cylinder resting upon the inside tracks on each side of said carriage, substantially as and for the purpose set forth.

In testimony whereof I affix my signature in presence of two witnesses.

CHARLES A. STARK.
